PUPPET

Russell B. Odell, Elgin, Ill., assignor to David C. Cook Publishing Company, Elgin, Ill.

Filed Sept. 11, 1972, Ser. No. 287,613

Term of patent 3½ years

Int. Cl. D21—01

U.S. Cl. D34—2 R

FIG. 1 is a front elevational view of a puppet embodying my new design;

FIG. 2 is a rear elevational view of my new design;

FIG. 3 is a side elevational view as seen from the left hand side in FIG. 1;

FIG. 4 is a side elevational view as seen from the right hand side in FIG. 1;

FIG. 5 is a top plan view; and

FIG. 6 is a bottom plan view of my new design.

I claim:

The ornamental design for a puppet, substantially as shown and described.
